Josef Stainer:

By E. G. Vrooman & Co.
his Attorneys,

UNITED STATES PATENT OFFICE.

JOSEF STAINER, OF PIERRE, SOUTH DAKOTA.

REINFORCED-CONCRETE BRIDGE STRUCTURE.

1,344,929.

Specification of Letters Patent. Patented June 29, 1920.

Application filed May 31, 1919. Serial No. 300,856.

To all whom it may concern:

Be it known that I, JOSEF STAINER, a citizen of the United States, residing at Pierre, in the county of Hughes and State of South Dakota, have invented certain new and useful Improvements in Reinforced-Concrete Bridge Structures, of which the following is a specification, reference being had therein to the accompanying drawings.

10 This invention relates to improvements in reinforced concrete bridge structures, and has for its object the improvement of the construction of a bridge formed of reinforced concrete, whereby the strength of 15 the bridge will be increased without materially increasing the cost of construction of the entire structure.

Another object of the invention is the strengthening of the span or side structures 20 of the bridge by a peculiar system of rods or bars, whereby a relatively small amount of material may be used in constructing the span or side structures thereby resulting in a material advantage by reason of reducing 25 the cost of construction of a bridge structure.

With these and other objects in view, my invention comprises certain novel constructions, combinations, and arrangements of 30 parts as will be hereinafter specifically described, illustrated in the accompanying drawings, and more particularly pointed out in the appended claims.

In the drawings,

35 Figure 1 is a view in elevation of a bridge structure constructed in accordance with the present invention, partly shown in full line and partly shown in section.

Fig. 2 is a view taken on line 2—2, Fig. 40 3, looking in the direction of the arrows.

Fig. 3 is a view taken on line 3—3, Fig. 2, looking in the direction of the arrows.

Fig. 4 is an enlarged sectional view taken on line 4—4, Fig. 1, looking in the direction 45 of the arrows.

Fig. 5 is a fragmentary perspective view of one of the transverse or primary beams showing the truss rods or bars passing under and through the same.

50 Fig. 6 is a bottom plan view of a bridge structure constructed in accordance with the present invention.

Referring to the drawings by numerals, 1, 1 designates the abutments, while 2, 2 are the 55 spans or side structures, and 3 is the floor structure.

The abutments 1 are formed of reinforced concrete, and built upon the abutments are side structures 2 and the floor 3.

Each side structure 2 comprises a vertical wall of concrete 4, and in each wall 4 is preferably a pair of primary truss rods or bars 5. In the lower portion of each side structure are preferably pairs of auxiliary truss rods or bars 6 and 7. For anchoring 65 the ends of the bars 5, 6, and 7 in the body of the sides, each bar is preferably bent at an angle, at its outer end, as shown at 8. Additional rods or bars, as shown by dotted lines 9 and 10, Fig. 1, are embedded in the 70 side structures for further reinforcing and strengthening said side structures.

The floor structure comprises transverse or primary I-beams 11 embedded at their ends in the side structures 2, and auxiliary 75 or longitudinally-extending I-beams 12 have their outer ends embedded in the upper portion of the abutments 1 and their inner ends fastened by plates 13 to the primary I-beams 11 (Fig. 4). If the bridge structure 80 is comparatively long, then additional auxiliary beams 12 are used between each two contiguous transverse or primary beams 11, and the auxiliary or longitudinally-extending beams 12 are fastened by plates 13, 85 as shown in Fig. 4, without departing from the spirit and scope of the present invention, as the addition of any number of primary or transverse beams and the auxiliary or longitudinally-extending beams 12 may be 90 involved, at the option of the constructor, without changing my invention.

At 14, Fig. 3, I have shown, in section, the webs of the primary and auxiliary I-beams to illustrate how these beams are 95 brought together, and held in said position by the angle plates 13 and the ordinary riveting of said plates and beams together.

Referring particularly to Figs. 1 and 5, the truss rods or bars 5, 6, and 7 are shown bent 100 downwardly at their middle, the rods or bars 5 passing through apertures 15 in the web of the transverse I-beam 11, and the rods or bars 6 and 7 pass under the I-beam, as shown (Fig. 5), thereby producing an 105 efficient truss that materially increases the strength of the bridge structure, and allows a comparatively low concrete side to be constructed, resulting in a material saving in the cost of construction. The numeral 16 110 designates the reinforced concrete surface of the bridge floor which is carried upon the

top of the transverse or primary beams 11 and the longitudinally-extending or auxiliary beams 12.

It will be understood that by reason of 5 the system of reinforcing the side structures of the bridge, the bridge is more strongly and effectively stiffened or strengthened, as a very efficient truss will be formed over the floor to carry the weight, since the 10 primary I-beams 11 are "suspended" in the concrete by the "suspending" or truss rods or bars 5, 6, and 7. I have preferably used two of the primary or transverse I-beams 11, but, as indicated hereinbefore, any number 15 can be employed in the construction of a bridge in accordance with the present invention, depending entirely upon the length or span of the bridge to be constructed.

From the foregoing description, it will be 20 understood that when carrying out my invention, in constructing a bridge, certain minor alterations or changes may appear to one skilled in the art to which this invention relates, and, therefore, I reserve the right to 25 make such minor alterations or changes as shall fairly fall within the scope of the appended claims.

What I claim is:

1. In a bridge structure of the class described, the combination with abutments, of side structures and a floor structure supported upon said abutments, said floor structure including transverse I-beams and longitudinally extending I-beams, said transverse I-beams having their ends embedded in the side structures, said longitudinally-extending I-beams having their outer ends embedded in portions of the floor and having 35 their inner ends fastened to the trans-

verse I-beams, a plurality of truss bars in 40 each side structure and bent downwardly near their middle, and some of said bars passing through the transverse I-beams and others of the bars passing under said I-beams near their ends. 45

2. In a bridge structure of the class described, the combination with abutments, of side structures and a floor structure including reinforcing I-beams having their ends extending into the side structures, and truss means embedded in the side structures and having their outer ends provided with anchoring means and being bent downwardly intermediate their ends and extending under the top of the reinforcing I-beams. 50 55

3. In a bridge structure of the class described, the combination with abutments, of side structures and a floor structure carried by said abutments, said floor structure including primary beams having webs and auxiliary beams secured to the webs of the primary beams near their top, a body of reinforced concrete carried by the upper portions of the primary and auxiliary beams, each of said side structures including 60 65 reinforcing horizontal rods or bars and a series of truss bars bent downwardly intermediate their ends and having their ends bent at an angle for constituting anchor means, and some of said truss bars having 70 their downwardly bent portions extending through the web of the primary beams and others of said truss bars extending under the primary beams, substantially as shown and described. 75

In testimony whereof I hereunto affix my signature.

JOSEF STAINER.
